(57) **CLAIM**

I claim the ornamental design for an exhaust muffler for automobile, as shown and described.

DESCRIPTION

FIG. 1 is a perspective view of an exhaust muffler for automobile of the present invention;

FIG. 2 is a front elevational view thereof (rear elevational view is identical);

FIG. 3 is a right side elevational view thereof (left side elevational view is identical); and,

FIG. 4 is a top plan view thereof (bottom plan view is identical).

In the drawings, the broken lines show portions of environmental structure that form no part of the claimed design.
